TRAY FOR HOLDING CONTAINERS FOR PLANTS

Arthur Hasselbach, Box 336, Cranbury, N.J. 08512

Filed Oct. 29, 1969, Ser. No. 19,828

Term of patent 14 years

Int. Cl. D11—02; D9—04

U.S. Cl. D35—3

FIG. 1 is a top plan view of a tray for holding containers for plants showing my new design;

FIG. 2 is a side elevational view thereof;

FIG. 3 is an end elevational view thereof; and

FIG. 4 is a cross-sectional view of FIG. 1 taken along the line 4—4 thereof.

I claim:

The ornamental design for a tray for holding containers for plants, as shown.
